UNITED STATES PATENT OFFICE.

ALBERT STEFFIN, OF NEW BEDFORD, MASSACHUSETTS, ASSIGNOR TO THE PAIRPOINT CORPORATION, OF NEW BEDFORD, MASSACHUSETTS.

DESIGN FOR OPEN-WORK BORDER FOR METALLIC TABLEWARE.

SPECIFICATION forming part of Design No. 36,829, dated March 1, 1904.

Application filed January 18, 1904. Serial No. 189,636. Term of patent 7 years.

To all whom it may concern:

Be it known that I, ALBERT STEFFIN, a citizen of the United States, residing at New Bedford, in the county of Bristol and State of Massachusetts, have invented a new, original, and ornamental Design for Open-Work Borders for Metallic Tableware, of which the following is a specification, reference being had to the accompanying drawing, forming part thereof.

The figure is a section of border adapted for

the edge of any suitable article of tableware, showing my new design.

What I claim as new, and desire to secure by Letters Patent, is—

The ornamental design for an open-work border for metallic tableware, as herein shown.

ALBERT STEFFIN.
